BODY SPLINT STRETCHER

John M. Liptay, Scarsdale, and Angelo Restivo, Jamaica, N. Y., assignors to Hospital Furniture Corporation, Long Island City, N. Y., a corporation of New York

Application December 4, 1943, Serial No. 512,852

1 Claim. (Cl. 5—82)

The subject matter of this invention is a litter or body splint stretcher for conveniently conveying the injured or wounded and specifically the invention is directed to a body splint stretcher advantageously adapted for utilization on ships, planes, in mines, industrial plants and in critical and dangerous localities. More particularly however the present invention is concerned with the type of splint stretcher disclosed in U. S. Letters Patents in Stokes 820,026 and MacKenzie 2,228,012. Hitherto in so far as we are aware litters of the type alluded to utilized a supporting frame wherein the supporting screen or lining sustaining the patient was in the form of so-called deformable and non-resilient chicken wire mesh. Such construction in actual practice has been found to have many functional and structural disadvantages; namely, chicken wire mesh is deformable but non-resilient hence, the weight or load of the previous patient appreciably deformed the contour of the screen thus providing undesirable projections and concavities to the annoyance of a following patient, furthermore the ends of the chicken wire mesh require coiling and clinching for securing thereof to a part of the frame thus apart from resulting in slow production, the laced or coiled ends of the wire mesh provide undesirable and needless extensions or projections characterizing sources of contact with the patient. Moreover where the chicken wire screen has been deformed over a protracted period of time in many instances it has been found that it becomes insufficient to support and maintain the patient thereon spatially free from the brace structure of the frame and in certain instances projections, such as stones or the like on the ground cause indentations in the screen providing objectionable inwardly extending projections serving as another source of annoyance to the patient. By the present invention, the above recited disadvantages are eliminated.

Thus the object of the invention is realized in the provision of an improved and serviceable body splint stretcher wherein the patient sustaining lining is in the form of a foraminous, relatively stiff, resilient sheet metal screen that is free of needless and undesirable projections that might cause injury to a patient pursuant to accident and wherein the perforated or foraminous screen is amply resilient to conform to the shape of the patient but is instantly automatically restored or retracted to its normal and desired contour following removal of the patient, hence

leaving or presenting no unnecessary indentations, concavities or projections which would characterize as hitherto stated sources of annoyance to the subsequent patient. The invention has as a further and important object to provide a relatively rugged and strong patient sustaining screen preformed from foraminous or perforated relatively thin sheet metal stock to provide a meshed and flexed patient sustaining lining held in spaced relation to the lower portions of the brace structure of the frame support and to afford by reason of its inherent resistance and tenacity ample protection from the ground and even from the lower brace portions of the frame. The invention further comprehends as an object the provision of a novel body splint stretcher wherein the marginal peripheral portions of the flexed lining or screen alluded to are encased or shielded by an appropriate band brazed to the metal braces of the frame. A further object resides in desirably securing the peripherally closed band to the upper part of the brace structure of the frame to permit the tapering sides and merged bottom wall of the one piece foraminous screen to depend from the band in spaced relation to the sides and bottom parts of the frame. Further objects, advantages, and functional structural features of the invention will appear from the following detailed specification considered in the light of the accompanying drawings where:

Fig. 1 is a perspective view of the litter or body splint stretcher according to our invention.

Fig. 2 is a side view of Fig. 1.

Fig. 3 is a plan view of Fig. 1.

Figs. 4 and 5 are transverse sectional views on the lines 4—4 and 5—5 of Fig. 3 respectively.

Fig. 6 is a fragmentary view of the expanded metal foraminous or perforated screen, and

Figs. 7 and 8 are sectional views on the lines 7—7 and 8—8 of Fig. 6 respectively.

Illustrative of the embodiment disclosed, the body splint stretcher or litter is generally denoted B and is characterized by a support or frame F, and a patient sustaining expanded metal foraminous screen S. Frame F comprises a peripherally closed metal rim or hand rail R to which are appropriately secured the spaced longitudinally arranged metal braces L and U shaped transverse metal braces T.

Suspended from the frame is the relatively thin, flat, foraminous or perforated and one piece sheet metal screen S. This screen may be formed from resilient plate or sheet metal which has been stretched or expanded widthwise and subse-

quently rolled to take the mesh illustrated in Fig. 6 and thus is characterized by a plurality of integrally merged hollow polygonal configurations generally denoted 10 defined by the relatively flat intersecting or merging ribs 11 disposed obliquely relatively to the longitudinal axis of the screen. As previously stated the biased or oblique ribs or bars 11 define the hollow polygonal portions 10 but all of these ribs are of the same sheet of metal and are integrally united or merged to form the perforated or foraminous screen although the merged parts 12 of adjacent configurations 10 as well as the inner and outer surfaces A and B' of the screen have been appropriately rolled to provide rectilinear or substantially flat and smooth surfaces.

To form the tensioned or flexed lining or screen S, it is appropriately shaped in a suitable press or the like and subsequent to processing, the diverging sides or wings 14, an inclined head rest or anterior portion 15, and closure 16 are formed to characterize a tensioned or flexed support substantially coextensive with the width and length of the frame. Even pursuant to processing the resilient screen presents relatively smooth inner and outer surfaces. In effect the screen subsequent to processing forms a basket for resiliently sustaining the patient and amply resistant to permanent localized deformations by reason of the load thereon or by inwardly and outwardly thrusts thereon.

For confining sharp projections which may be defined by the peripheral border or margin M of the screen pursuant to processing, this border is concealed and reinforced by an inverted U-shaped sheath or band 17 which extends along the head rest 15, the diverged and spaced sides 14, and the closure end 16, thus providing a reinforcing rim having the spaced legs 18 and 19, snugly and closely straddling the peripheral margin or border M of the screen.

For firmly securing the reinforcing band 17 to the screen, side 18 thereof is adequately provided with spaced indentations or depressed portions 20 for reception into an opening 21 of the hollow polygonal portions and thus interlocking therewith, consequently positioning the peripheral band 17 along the screen after which legs 18 and 19 are welded together at spaced portions 22 to snugly enclose adjacent portions of diverged branches of the margin M. By the present construction a relatively smooth, durable and reinforcing band is provided to preclude access to any sharp projections by the patient thus the latter is shielded against injury.

Slippage of the patient sustaining screen longitudinally, transversely or vertically relative to the frame F is precluded by appropriately welding the reinforcing band 17 to the upper portions 23 of longitudinal and transverse braces L and T, hence the diverged sides 14 and the slightly curved bottom wall 24 of the screen are appreciably spaced from braces L and T.

The usual straps 25 to hold the patient are mounted across the sides of the hand rail R 65 while a suitable offset rod 26 is securely arranged longitudinally of the screen to act as an adequate intervenor for the legs of the patient.

It should be observed that the screen is located slightly below the hand rail R and except where the band 17 is secured to the upper portions of the braces of the frame the sheet metal foraminous or perforated screen according to the invention has its diverging sides or wings 14 spaced from the braces L and T of the frame and similarly the bottom wall 24 of the screen is appreciably spaced from the lower brace structure of the frame. Even when a patient is within the frame, the screen is of adequate strength to sustain the patient from reaching the braces, the screen however is amply resilient to conform to the form of the patient and instantly is restored to its normal contour upon removal of the patient. If desired diagonal brace D may be secured along the sides of the frame for reinforcing the latter. Moreover even though in actual practice the screen is of sufficient resilience and resistance requiring no underneath sag preventing conventional type platform (not shown) usually interposed between the bottom wall of the screen and the bottom part of the frame, such platform may be employed if desired. The brace structure characterized by braces L and T and hand rail R of the frame are of suitable metal and band 17 is confined within the frame spaced from the hand rail. The screen may be said to depend from the band with its tapered sides spaced from the sides of the frame and its bottom wall spaced from the lower part of the frame.

Many changes can be made in the herein construction and many widely different species of structural embodiments of the invention can be devised without departing from the scope thereof. It is therefore intended that all matter herein described in the specification and illustrated in the accompanying drawings shall be interpreted as illustrative and not in a limiting sense.

We claim:

In a body splint stretcher, a frame comprising longitudinally arranged brace means and transversely disposed brace means defining upwardly diverging spaced sides and a bottom brace structure, a rail secured to the upper end of said brace means, a substantially peripherally closed and inverted U shaped band within said frame and spaced and disposed below said rail and characterizing a sheath having spaced legs defining a gap, a one piece relatively thin preformed perforated and sensibly resilient depending expanded sheet metal screen arranged within said frame and having an upper marginal portion disposed in said gap and having upwardly diverging side walls spaced from said diverging sides and a bottom wall spaced from said brace structure; said side walls, bottom wall and marginal portion having a plurality of hollow substantially diamond shaped configurations, indent means extending from said band interlocking with several of said configurations of said marginal portion, and means securing said band to said brace means.
